UNITED STATES PATENT OFFICE.

WILLIAM C. LEA, OF LOS ANGELES, CALIFORNIA.

CASEMENT-ADJUSTER.

Specification of Letters Patent.

Patented Dec. 31, 1918.

1,289,828.

Application filed March 18, 1918. Serial No. 223,241.

To all whom it may concern:

Be it known that I, WILLIAM C. LEA, a citizen of the United States, residing at Los Angeles, in the county of Los Angeles, State of California, have invented a new and useful Casement-Adjuster, of which the following is a specification.

My invention relates to casement adjusters, being more particularly a device for opening and closing casements and fixing the casement in either extreme position or intermediate positions.

The principal object of my invention is to produce a casement adjuster of simple form and construction which may be attached to the ordinary form of window construction.

Other objects and advantages will appear hereinafter from the following description and drawings.

Referring to the drawings, which are for illustrative purposes only,

Figure 1 is a sectional plan view of a casement frame showing a device embodying a form of my invention mounted thereon.

Fig. 2 is a view similar to Fig. 1 showing the casement in open position.

Fig. 3 is a plan view of a portion of the adjuster, partly in section.

Fig. 4 is a sectional view on line 4-4, Fig. 1.

Fig. 5 is a sectional view on line 5-5, Fig. 1.

Fig. 6 is a sectional view on line 6-6, Fig. 4, and

Fig. 7 is a perspective view of a swivel block and follower.

The mechanism for operating the casement is largely contained within a casing designated at 11, which casing consists of a base plate 12 and a cover 13 shaped like a box and having flanges 14 which receive screws 15 which extend through the base plate 12 into the sill 16.

The frame of which the sill 16 forms a part is of ordinary construction having jambs 17 to one of which is mounted, by means of suitable hinges 18, a casement sash 19, said sash being mounted to swing outwardly from the frame.

In the form shown, the operating mechanism or adjuster is concealed, that is, the adjuster is covered by means of a stool 20, a filler block 21 being provided between the stool and the sill leaving a space or chamber sufficiently large to receive the casing

or box 11, and in the form shown, the apron 22 extends a sufficient distance upward to engage the under side of the stool 20, a portion of the upper, inner edge of the apron 22 being cut away, as indicated at 23, to accommodate the casing 11. It is, however, to be understood that installations of the adjuster may be made on the common window frames without concealing the adjuster as above described, in which case the casing 11 would be mounted directly on the stool.

Secured to the inner face of the sash 19 is a guide 25 in which is slidably mounted a guide block 26, the lower edges of the guide 25 being turned inwardly, as indicated at 27 in Fig. 5, to retain the block 26 therein. The guide block 26 is pivotally mounted by means of a pin 28 on the outer end of an operating bar 29, the inner end of the bar 29 extending through an opening 30 in the cover of the box 11 where it is provided with an offset portion 31 pivotally mounted to the base plate 12 by means of a stud 32 mounted in the said base plate.

35 designates a nut mounted to travel on the threaded end of a shaft 36. The nut 35 is provided with upper and lower trunnions 37 and 38 respectively, the lower trunnion 38 extending into the operating bar 29 and the upper trunnion 37 extending into a bracket 39 which is secured to the upper face of the bar 29 by means of a bolt or rivet 40, and also by means of the stud 32 which extends through said bracket 39. By the construction just described it is evident that the nut 35 is swiveled between the bracket 39 and the operating bar 29, the trunnions 37 and 38 permitting the nut 35 to swing freely between the said operating bar and bracket.

42 designates a swivel block which engages a reduced portion 43 of the shaft 36, there being a shoulder at each end of the reduced portion 43 engaging the opposite faces of the swivel block 42 thereby retaining the shaft 100 in the swivel block, permitting the turning of the same therein, but preventing any longitudinal movement of the shaft in the swivel block. 44 designates a trunnion on the lower end of the swivel block 42, which extends into the base plate 12. 45 designates a follower which fits into a recess 46 in the upper face of the swivel block 42, the follower being cut out, as indicated at 47, to fit over the reduced portion 43 of the shaft 36. 110 The follower 45 is provided with a trunnion 48 which extends into a bracket 50 which

bracket 50 is secured to the base plate 12 by means of suitable bolts or screws 51. By the construction of the swivel block 42 and the mounting of the same as just described, 5 it will appear that the swivel block 42 may freely turn on its trunnions between the base plate 12 and the block 50, the swivel block comprising a mounting for the shaft 36.

The inner end of the shaft 36 is squared, 10 as indicated at 53, and extends through an opening 54 formed in the apron 22 to the inside of the frame where it may readily be engaged by means of a suitable crank 55 for the operation of the device as hereafter described.

The adjuster works in the following manner:

A crank 55 being placed upon the squared end of the shaft, and assuming that the parts 20 are in the position shown in Fig. 1, by turning the shaft with the crank the nut 35 is moved on the threaded end of the shaft 36 toward the swivel block 42. This operation swings the bar 29 about the stud 32, 25 and a continuation of this movement brings the parts into the position shown in Fig. 2 of the drawing, in which position the casement window is fully opened. During this 30 operation the guide block 26 slides in the guide 25 on the sash from the position indicated in Fig. 1 to that shown in Fig. 2.

It is to be understood that the sash may be placed in any intermediate position between the two positions shown in Figs. 1 and 2 and 35 that in any position the sash is rigid, there being no links or intermediate connections between the operating bar and the shaft 36 except the nut 35 which is directly mounted upon the operating bar, as heretofore described.

It is further to be understood that I do not limit my invention to the operation of casement sashes as heretofore described, but it 45 will readily appear to those skilled in the art that the same mechanism may be mounted upon transoms for the operation of the same.

What I claim is:—

1. A casement adjuster comprising a base 50 plate secured to the casement frame, a swivel block mounted on said base plate, a screw having an intermediate reduced portion en-

gaged in said swivel block, a nut on said screw, a bar pivotally mounted on said base plate, means for pivotally mounting said nut 55 directly on said bar, a guide block pivotally mounted on the outer end of said bar, and a guide mounted on the casement sash arranged to slidably engage said guide block.

2. A casement adjuster comprising a base 60 plate secured to the casement frame, a swivel block mounted on said base plate, a screw having an intermediate reduced portion engaged in said swivel block, a nut on said screw, a bar pivotally mounted on said 65 base plate, means for pivotally mounting said nut directly on said bar, and means for slidably connecting said bar to the casement sash.

3. A casement adjuster comprising a base 70 plate secured to the casement frame, a swivel block pivotally mounted on said base plate, a threaded shaft mounted against longitudinal movement in said block, a nut mounted on the threaded end of said shaft, an operating 75 bar pivotally mounted on said base plate, a bracket fixed on said bar, trunnions on said nut engaging said bar and said bracket, a guide secured to the casement sash, and means on said bar for slidably engaging 80 said guide.

4. A casement adjuster comprising a casing secured to the casement frame, said casing consisting of a base plate and a cover 85 thereon, a swivel block mounted in said casing, a threaded shaft having a reduced portion mounted in the swivel block, a squared inner end on said shaft extending through an opening in said casing, a traveling nut mounted on the threaded portion of said 90 shaft, an operating bar pivotally mounted to the base plate within said casing, a swivel connection for mounting said nut on said bar, said bar extending through an opening in said casing, a guide secured to said casement 95 having a slot in its under side, a guide block, and a pin on said bar extending through the slot in the guide to pivotally mount the guide block on said bar.

In testimony whereof, I have hereunto set 100 my hand at Los Angeles, California, this 7th day of March, 1918.

WILLIAM C. LEA.
